UNITED STATES PATENT OFFICE

170,780

PLASTER CAST SPREADING TOOL

Thomas C. Ward, Waco, Tex.

Application August 1, 1952, Serial No. 20,879

Term of patent 14 years

(Cl. D54—13)

To all whom it may concern:

Be it known that I, Thomas C. Ward, a citizen of the United States, residing at Waco, in the county of McLennan and State of Texas, have invented a new, original, and ornamental Design for a Plaster Cast Spreading Tool, of which the following is a specification, reference being had to the accompanying drawing, forming part thereof.

Figure 1 is a top plan view of a plaster cast spreading tool, showing my new design;

Figure 2 is a side edge view thereof;
Figure 3 is a front end view; and

Fig. 4 is a rear end view of the same.

I claim:

The ornamental design for a plaster cast spreading tool, as shown.

THOMAS C. WARD.
